United States Patent Office

Des. 193,043

Patented June 12, 1962

193,043

DISPLAY RACK

Arthur Talmadge, New York, N.Y., assignor to United Artists Records, Inc., New York, N.Y., a corporation of Delaware

Filed Oct. 16, 1961, Ser. No. 67,092

Term of patent 7 years

(Cl. D80—5)

FIG. 1

FIG. 3

FIG. 1 is a front elevational view of a display rack showing my new design;

FIG. 2 is a side elevational view thereof; and

FIG. 3 is a rear elevational view thereof.

I claim:

The ornamental design for a display rack, as shown.
